UNITED STATES PATENT OFFICE.

HARRY F. BUSHONG, OF KALAMAZOO, MICHIGAN, ASSIGNOR, BY DIRECT AND MESNE ASSIGNMENTS, TO KALAMAZOO LOOSE LEAF LEDGER COMPANY, A CORPORATION.

TEMPORARY BINDER OR LOOSE-SHEET HOLDER.

SPECIFICATION forming part of Letters Patent No. 794,778, dated July 18, 1905.

Application filed July 13, 1904. Serial No. 216,350.

To all whom it may concern:

Be it known that I, HARRY F. BUSHONG, a citizen of the United States, residing at the city of Kalamazoo, in the county of Kalamazoo and State of Michigan, have invented certain new and useful Improvements in Temporary Binders or Loose-Sheet Holders, of which the following is a specification.

This invention relates to improvements in temporary binders.

The objects of this invention are, first, to provide an improved temporary binder for sheets or leaves by which the sheets or leaves are securely held without being specially prepared therefor and without in any manner mutilating the same and one in which the sheets may be quickly inserted or removed; second, to provide an improved temporary binder or loose-sheet holder which is simple and economical in construction and convenient and durable in use.

Further objects and objects relating to structural details will definitely appear from the detailed description to follow.

I accomplish the objects of my invention by the devices and means described in the following specification.

The invention is clearly defined and pointed out in the claims.

A structure embodying the features of my invention is clearly illustrated in the accompanying drawings, forming a part of this specification, in which—

Figure 1 is a perspective view of my improved temporary binder or loose - sheet holder illustrated with a number of sheets in position therein. Fig. 2 is a rear elevation view of the same. Fig. 3 is a side elevation view looking from the right of Fig. 2, the leaves or sheets being removed and the movement of the parts being indicated by dotted lines. Fig. 4 is a detail sectional view taken on a line corresponding to line 4 4 of Figs. 2 and 5, the movement of the parts being indicated by dotted lines. Fig. 5 is a detail sectional view taken on a line corresponding to line 5 5 of Fig. 4 with one end of the pin D shown in section, the tension-spring D' being

shown in full lines. Fig. 6 is a detail sectional view taken on a line corresponding to line 6 6 of Fig. 5, the leaf or sheet clamping jaw being shown in its open position, showing the means for actuating the locking dog or lever E. Fig. 7 is a detail sectional view taken on a line corresponding to line 7 7 of Fig. 5 with the sheet - clamping jaw in its open position, showing the locking dog or lever in its engaging position.

In the drawings the sectional views are taken looking in the direction of the little arrows at the ends of the section-lines, and similar letters of reference refer to similar parts throughout the several views.

Referring to the drawings, I provide a relatively stationary cover A and a swinging cover A'. These covers are provided with rearwardly - projecting hinge - pieces a and a', respectively, which are rigidly secured thereto. A pin D is carried by the hinge-pieces a. Upwardly-projecting links B' B'' are journaled on the pin D. These links are rigidly secured together by a cross - bar B, as clearly appears in Fig. 1. The hinge-pieces a' of the cover A' are pivotally secured to the upper ends of these links B' B''.

75

Upon the pin or shaft D is a cylinder C, having a forwardly-projecting clamping-jaw or sheet-holder C' thereon. This cylinder C is connected to the pin D by the coiled spring D', which is arranged upon the pin. One end of this coiled spring D' is connected to the pin and the other to the cylinder. This tension-spring holds the clamping - jaw normally against the cover A, and the sheets are clamped between it and the cover. One end of the pin D is provided with a longitudinal keyhole, (see Fig. 5,) in which the key is illustrated by dotted lines for adjusting the tension of the spring. In adjusting the tension of the spring the right-hand hinge-piece a, which is provided with a square or irregular hole to receive the square or irregular end of the pin D, is removed from the pin, which releases the same. The tension of the spring may then be increased or lessened, as desired, by turning the pin. When satisfactorily adjusted, the

80

85

90

95

hinge-piece is again secured in position, which prevents the turning of the pin.

A pawl *b* is slidably mounted upon the cross-bar *B*, so that it may be adjusted into and out of its operative or engaging position. When in its engaging position, this pawl is adapted to engage the tooth or lug *c* on the cylinder *C*. A stop *b'* is provided on the cross-bar *B* for this pawl *b*. When it is desired to release the clamping-jaw, the pawl *b* is shifted against the stop and the cover *A'* is opened and carried rearwardly and downwardly, as indicated by dotted lines in Fig. 4. The pawl engaging the lug or tooth *c* on the cylinder opens the clamping-jaw against the tension of the spring *D'*.

A locking dog or lever *E*, adapted to engage a notch *g* in the cylinder *C* to retain it in its open position, is provided. The locking dog or lever *E* is pivoted on the cover *A*. This locking dog or lever is thrown into engagement with the notch *g* by a cam *c''*, projecting from the cylinder. As the cylinder is revolved this cam *c''* engages the inner end *e* of the dog or lever *E* and throws its outer end *e'* into engagement with the notch *g*. The locking dog or lever *E* is released by the cam projection *f* on the link *B'*, which as the cover *A'* is returned to its closed position engages the projection *c''* on the locking-dog and forces it from the notch *g*, thus freeing the cylinder and allowing the tension-spring to return it to its initial position and clamp it down upon the cover *A* or the sheets placed thereon. As the cover *A'* is returned to its closed position the pawl *b* is engaged by the cam *c* on the cylinder, by which it is shifted to its initial or normal position. When the pawl *b* is in its initial or normal position, the cover *A'* may be opened and closed without affecting the clamping-jaw. When it is again desired to release or open the clamping-jaw, the pawl *b* is shifted against the stop *b'* and the cover manipulated, which opens the clamping-jaw, as before described.

The cam *c* is so shaped that when the pawl *b* is in its engaging position it rides over the same and drops into engagement with the tooth or lug *c*. The pawl *b* is preferably formed of spring metal, so that it readily travels over the cam *c* and snaps into engagement with the tooth *c*. When formed of spring metal, it also grips the cross-bar *B* sufficiently to prevent its being accidentally shifted.

By my improved temporary binder or loose-leaf holder I am enabled to retain the leaves or sheets securely without the necessity of any special preparation of the sheets therefor and without in any manner mutilating the same. At the same time the leaves or sheets are quickly and easily inserted or removed from the holder.

I have illustrated and described my improved temporary binder or loose-sheet holder in detail in the form preferred by me on ac-

count of its structural simplicity and durability and the economy of producing the same. I am, however, aware that it is capable of considerable structural variation without departing from my invention.

Having thus described my invention, what I claim as new, and desire to secure by Letters Patent, is—

1. The combination of a relatively stationary cover and a swinging cover; rearwardly-projecting rigid hinge-pieces for said covers; a pin carried by the hinge-pieces of said stationary cover; upwardly-projecting links to which the hinge-pieces of said swinging cover are pivotally secured, mounted on said pin; a cross-bar connecting said links; a cylinder having a forwardly-projecting clamping-jaw thereon, mounted on said pin; a spring connected to said pin and to said cylinder for applying tension thereto, whereby said clamping-jaw is held normally against said stationary cover; a pawl slidably mounted on said cross-bar so that it may be shifted into or out of its engaging position; a projecting tooth or lug on said cylinder adapted to be engaged by said pawl when it is adjusted to its engaging position; a cam on said cylinder for returning said pawl to its initial position; a locking lever or dog on said stationary cover, adapted to engage said cylinder for locking it in its open position; a cam on said cylinder for actuating said locking lever or dog; and a cam on one of said links for releasing said locking lever or dog, for the purpose specified.

2. The combination of a relatively stationary cover and a swinging cover; rearwardly-projecting rigid hinge-pieces for said covers; a pin carried by the hinge-pieces of said stationary cover; upwardly-projecting links to which the hinge-pieces of said swinging cover are pivotally secured, mounted on said pin; a cross-bar connecting said links; a cylinder having a forwardly-projecting clamping-jaw thereon, mounted on said pin; a spring connected to said pin and to said cylinder for applying tension thereto, whereby said clamping-jaw is held normally against said stationary cover; a pawl slidably mounted on said cross-bar so that it may be shifted into or out of its engaging position; a projecting tooth or lug on said cylinder adapted to be engaged by said pawl when it is adjusted to its engaging position; a locking lever or dog on said stationary cover, adapted to engage said cylinder for locking it in its open position; a cam on said cylinder for actuating said locking lever or dog; and a cam on one of said links for releasing said locking lever or dog, for the purpose specified.

3. The combination of a relatively stationary cover and a swinging cover; rearwardly-projecting rigid hinge-pieces for said covers; a pin carried by the hinge-pieces of said stationary cover; upwardly-projecting links to which the hinge-pieces of said swinging cover

are pivotally secured, mounted on said pin; a cross-bar connecting said links; a cylinder having a forwardly-projecting clamping-jaw thereon, mounted on said pin; a spring connected to said pin and to said cylinder for applying tension thereto, whereby said clamping-jaw is held normally against said stationary cover; a pawl slidably mounted on said cross-bar so that it may be shifted into or out of its engaging position; a projecting tooth or lug on said cylinder, adapted to be engaged by said pawl when it is adjusted to its engaging position; a locking lever or dog on said stationary cover, adapted to engage said cylinder for locking it in its open position; and a cam on one of said links for releasing said locking lever or dog, for the purpose specified.

4. The combination of a relatively stationary cover and a swinging cover; rearwardly-projecting rigid hinge-pieces for said covers; a pin carried by the hinge-pieces of said stationary cover; upwardly-projecting links to which the hinge-pieces of said swinging cover are pivotally secured, mounted on said pin; a cross-bar connecting said links; a cylinder having a forwardly-projecting clamping-jaw thereon, mounted on said pin; a spring connected to said pin and to said cylinder for applying tension thereto, whereby said clamping-jaw is held normally against said stationary cover; a pawl slidably mounted on said cross-bar so that it may be shifted into or out of its engaging position; a locking lever or dog on said stationary cover, adapted to engage said cylinder for locking it in its open position; and a cam on one of said links for releasing said locking lever or dog, for the purpose specified.

40 5. The combination of a relatively stationary cover and a swinging cover; rearwardly-projecting rigid hinge-pieces for said covers; a pin carried by the hinge-pieces of said stationary cover; upwardly-projecting links to which the hinge-pieces of said swinging cover are pivotally secured, mounted on said pin; a cross-bar connecting said links; a cylinder having a forwardly-projecting clamping-jaw thereon, mounted on said pin; a spring connected to said pin and to said cylinder for applying tension thereto, whereby said clamping-jaw is held normally against said stationary cover; a pawl slidably mounted on said cross-bar, so that it may be shifted into or out of its engaging position; a projecting tooth or lug on said cylinder, adapted to be engaged by said pawl when it is adjusted to its engaging position; a cam on said cylinder for returning said pawl to its initial position; a locking lever or dog on said stationary cover, adapted to engage said cylinder for locking it in its open position; and a cam on said cylinder for actuating said locking dog or lever, for the purpose specified.

65 6. The combination of a relatively station-

ary cover and a swinging cover; rearwardly-projecting rigid hinge-pieces for said covers; a pin carried by the hinge-pieces of said stationary cover; upwardly-projecting links to which the hinge-pieces of said swinging cover are pivotally secured, mounted on said pin; a cross-bar connecting said links; a cylinder having a forwardly-projecting clamping-jaw thereon, mounted on said pin; a spring connected to said pin and to said cylinder for applying tension thereto, whereby said clamping-jaw is held normally against said stationary cover; a pawl slidably mounted on said cross-bar so that it may be shifted into or out of its engaging position; a projecting tooth or lug on said cylinder, adapted to be engaged by said pawl when it is adjusted to its engaging position; a locking lever or dog on said stationary cover, adapted to engage said cylinder for locking it in its open position; and a cam on said cylinder for actuating said locking lever or dog, for the purpose specified.

70 7. The combination of a relatively stationary cover and a swinging cover; rearwardly-projecting rigid hinge-pieces for said covers; a pin carried by the hinge-pieces of said stationary cover; upwardly-projecting links to which the hinge-pieces of said swinging cover are pivotally secured, mounted on said pin; a cross-bar connecting said links; a cylinder having a forwardly-projecting clamping-jaw thereon, mounted on said pin; a spring connected to said pin and to said cylinder for applying tension thereto, whereby said clamping-jaw is held normally against said stationary cover; a pawl slidably mounted on said cross-bar so that it may be shifted into or out of its engaging position; a projecting tooth or lug on said cylinder, adapted to be engaged by said pawl when it is adjusted to its engaging position; a cam on said cylinder for returning said pawl to its initial position; a locking lever or dog on said stationary cover, adapted to engage said cylinder for locking it in its open position; for the purpose specified.

75 8. The combination of a relatively stationary cover and a swinging cover; rearwardly-projecting rigid hinge-pieces for said covers; a pin carried by the hinge-pieces of said stationary cover; upwardly-projecting links to which the hinge-pieces of said swinging cover are pivotally secured, mounted on said pin; a cross-bar connecting said links; a cylinder having a forwardly-projecting clamping-jaw thereon, mounted on said pin; a spring connected to said pin and to said cylinder for applying tension thereto, whereby said clamping-jaw is held normally against said stationary cover; a pawl slidably mounted on said cross-bar, so that it may be shifted into or out of its engaging position; a projecting tooth or lug on said cylinder adapted to be engaged by said pawl when it is adjusted to its engaging position; and a locking lever or dog on

said stationary cover adapted to engage said cylinder for locking it in its open position, for the purpose specified.

9. The combination of a relatively stationary cover and a swinging cover; rearwardly-projecting rigid hinge-pieces for said covers; a pin carried by the hinge-pieces of said stationary cover; upwardly-projecting links to which the hinge-pieces of said swinging cover are pivotally secured, mounted on said pin; a cross-bar connecting said links; a cylinder having a forwardly-projecting clamping-jaw thereon, mounted on said pin; a spring connected to said pin and to said cylinder for applying tension thereto, whereby said clamping-jaw is held normally against said stationary cover; a pawl slidably mounted on said cross-bar so that it may be shifted into or out of its engaging position; a projecting tooth or lug on said cylinder adapted to be engaged by said pawl when it is adjusted to its engaging position; and a cam on said cylinder for returning said pawl to its initial position, for the purpose specified.

25 10. The combination of a relatively stationary cover and a swinging cover; rearwardly-projecting rigid hinge-pieces for said covers; a pin carried by the hinge-pieces of said stationary cover; upwardly-projecting links to which the hinge-pieces of said swinging cover are pivotally secured, mounted on said pin; a cross-bar connecting said links; a cylinder having a forwardly-projecting clamping-jaw thereon, mounted on said pin; a spring connected to said pin and to said cylinder for applying tension thereto, whereby said clamping-jaw is held normally against said stationary cover; a pawl slidably mounted on said cross-bar, so that it may be shifted into or out of its engaging position; and a projecting tooth or lug on said cylinder adapted to be engaged by said pawl when it is adjusted to its engaging position, for the purpose specified.

45 11. The combination of a relatively stationary cover and a swinging cover; a pin carried by said stationary cover; upwardly-projecting links to which said swinging cover is pivotally secured, mounted on said pin; a clamping-jaw mounted on said pin; a spring connected to said pin and to said clamping-jaw for applying tension thereto, whereby said clamping-jaw is held normally against said stationary cover; an adjustable pawl carried by said links adapted to be shifted into or out of its engaging position; a projecting tooth or lug connected with said clamping-jaw adapted to be engaged by said pawl when it is adjusted to its engaging position; a cam connected with said clamping-jaw for returning said pawl to its initial position; a locking dog or lever on said stationary cover for locking it in its open position; a cam connected with said clamping-jaw for actuating said locking dog or lever;

and a cam on one of said links for releasing 65 said locking-dog, for the purpose specified.

12. The combination of a relatively stationary cover and a swinging cover; a pin carried by said stationary cover; upwardly-projecting links to which said swinging cover is pivotally 70 secured, mounted on said pin; a clamping-jaw mounted on said pin; a spring connected to said pin and to said clamping-jaw for applying tension thereto, whereby said clamping-jaw is held normally against said stationary 75 cover; an adjustable pawl carried by said links adapted to be shifted into or out of its engaging position; a projecting tooth or lug connected with said clamping-jaw adapted to be 80 engaged by said pawl when it is adjusted to its engaging position; a locking dog or lever on said stationary cover for locking it in its open position; a cam connected with said clamping-jaw for actuating said locking dog or lever; and a cam on one of said links for 85 releasing said locking-dog, for the purpose specified.

13. The combination of a relatively stationary cover and a swinging cover; a pin carried by said stationary cover; upwardly-projecting 90 links to which said swinging cover is pivotally secured, mounted on said pin; a clamping-jaw thereon mounted on said pin; a spring connected to said pin and to said clamping-jaw for applying tension thereto, whereby said 95 clamping-jaw is held normally against said stationary cover; an adjustable pawl carried by said links adapted to be shifted into or out of its engaging position; a projecting tooth or lug connected with said clamping-jaw adapted 100 to be engaged by said pawl when it is adjusted to its engaging position; a cam connected with said clamping-jaw for returning said pawl to its initial position; a locking dog or lever on said stationary cover for locking it in its open 105 position; and a cam on one of said links for releasing said locking-dog, for the purpose specified.

14. The combination of a relatively stationary cover and a swinging cover; a pin carried 110 by said stationary cover; upwardly-projecting links to which said swinging cover is pivotally secured, mounted on said pin; a clamping-jaw thereon mounted on said pin; a spring connected to said pin and to said clamping-jaw 115 for applying tension thereto, whereby said clamping-jaw is held normally against said stationary cover; an adjustable pawl carried by said links adapted to be shifted into or out of its engaging position; a projecting tooth or lug connected with said clamping-jaw adapted 120 to be engaged by said pawl when it is adjusted to its engaging position; a locking dog or lever on said stationary cover for locking it in its open position; and a cam on one of said links 125 for releasing said locking-dog, for the purpose specified.

15. The combination of a relatively station-

- ary cover and a swinging cover; a pin carried by said stationary cover; upwardly-projecting links to which said swinging cover is pivotally secured, mounted on said pin; a clamping-jaw 5 thereon mounted on said pin; a spring connected to said pin and to said clamping-jaw for applying tension thereto, whereby said clamping-jaw is held normally against said stationary cover; an adjustable pawl carried 10 by said links adapted to be shifted into or out of its engaging position; a projecting tooth or lug on said clamping-jaw adapted to be engaged by said pawl when it is adjusted to its engaging position; a cam connected with said 15 clamping-jaw for returning said pawl to its initial position; a locking dog or lever on said stationary cover for locking the clamp in its open position; and a cam connected with said clamping-jaw for actuating said locking dog 20 or lever; for the purpose specified.
16. The combination of a relatively stationary cover and a swinging cover; a pin carried by said stationary cover; upwardly-projecting links to which said swinging cover is pivotally 25 secured, mounted on said pin; a clamping-jaw thereon mounted on said pin; a spring connected to said pin and to said clamping-jaw for applying tension thereto, whereby said clamping-jaw is held normally against said 30 stationary cover; an adjustable pawl carried by said links adapted to be shifted into or out of its engaging position; a projecting tooth or lug connected with said clamping-jaw adapted to be engaged by said pawl when it is adjusted 35 to its engaging position; a locking dog or lever on said stationary cover for locking it in its open position; and a cam connected with said clamping-jaw for actuating said locking dog or lever, for the purpose specified.
- 40 17. The combination of a relatively stationary cover and a swinging cover; a pin carried by said stationary cover; upwardly-projecting links to which said swinging cover is pivotally secured, mounted on said pin; a clamping-jaw 45 thereon mounted on said pin; a spring connected to said pin and to said clamping-jaw for applying tension thereto, whereby said clamping-jaw is held normally against said stationary cover; an adjustable pawl carried by said links 50 adapted to be shifted into or out of its engaging position; a projecting tooth or lug connected with said clamping-jaw adapted to be engaged by said pawl when it is adjusted to its engaging position; a cam connected with 55 said clamping-jaw for returning said pawl to its initial position; and a locking dog or lever on said stationary cover for locking it in its open position, for the purpose specified.
- 60 18. The combination of a relatively stationary cover and a swinging cover; a pin carried by said stationary cover; upwardly-projecting links to which said swinging cover is pivotally secured, mounted on said pin; a clamping-jaw 65 mounted on said pin; a spring connected to said pin and to said clamping-jaw for applying

ing tension thereto, whereby said clamping-jaw is held normally against said stationary cover; an adjustable pawl carried by said links adapted to be shifted into or out of its engaging position; a projecting tooth or lug connected with said clamping-jaw adapted to be engaged by said pawl when it is adjusted to its engaging position; and a locking dog or lever on said stationary cover for locking it in its open position, for the purpose specified. 70 75

19. The combination of a relatively stationary cover and a swinging cover; a pin carried by said stationary cover; upwardly-projecting links to which said swinging cover is pivotally secured, mounted on said pin; a clamping-jaw 80 mounted on said pin; a spring connected to said pin and to said clamping-jaw for applying tension thereto, whereby said clamping-jaw is held normally against said stationary cover; an adjustable pawl carried by said links 85 adapted to be shifted into or out of its engaging position; a projecting tooth or lug connected with said clamping-jaw adapted to be engaged by said pawl when it is adjusted to its engaging position; and a cam connected 90 with said clamping-jaw for returning said pawl to its initial position, for the purpose specified.

20. The combination of a relatively stationary cover and a swinging cover; a pin carried by said stationary cover; upwardly-projecting links to which said swinging cover is pivotally secured, mounted on said pin; a clamping-jaw mounted on said pin; a spring connected to said pin and to said clamping-jaw for applying tension thereto, whereby said clamping-jaw is held normally against said stationary cover; an adjustable pawl carried by said links 100 adapted to be shifted into or out of its engaging position; and a projecting tooth or lug 105 connected with said clamping-jaw adapted to be engaged by said pawl when it is adjusted to its engaging position, for the purpose specified.

21. The combination of a relatively stationary cover and a swinging cover; a pin carried by said stationary cover; upwardly-projecting links to which said swinging cover is pivotally secured, mounted on said pin; a clamping-jaw mounted on said pin; a spring connected to 110 said pin and to said clamping-jaw for applying tension thereto, whereby said clamping-jaw is held normally against said stationary cover; an adjustable pawl carried by said links 115 adapted to be shifted into or out of operative position; a projecting tooth or lug connected with said clamping-jaw adapted to be engaged by said pawl when it is adjusted to its operative position; a cam connected with said clamping-jaw for returning said pawl to its initial 120 position; a dog for locking said clamping-jaw in its open position; and a cam on one of said links for releasing said dog, for the purpose specified.

22. The combination of a relatively station- 130

ary cover and a swinging cover; a pin carried by said stationary cover; upwardly-projecting links to which said swinging cover is pivotally secured, mounted on said pin; a clamping-jaw mounted on said pin; a spring connected to said pin and to said clamping-jaw for applying tension thereto, whereby said clamping-jaw is held normally against said stationary cover; an adjustable pawl carried by said links adapted to be shifted into or out of its operative position; a projecting tooth or lug connected with said clamping-jaw adapted to be engaged by said pawl when it is adjusted to its operative position; a dog for locking said clamping-jaw in its open position; and a cam on one of said links for releasing said dog, for the purpose specified.

23. The combination of a relatively stationary cover and a swinging cover; a pin carried by said stationary cover; upwardly-projecting links to which said swinging cover is pivotally secured, mounted on said pin; a clamping-jaw mounted on said pin; a spring connected to said pin and to said clamping-jaw for applying tension thereto, whereby said clamping-jaw is held normally against said stationary cover; an adjustable pawl carried by said links adapted to be shifted into or out of its operative position; a projecting tooth or lug connected with said clamping-jaw adapted to be engaged by said pawl when it is adjusted to its operative position; a cam connected with said clamping-jaw for returning said pawl to its initial position; and a cam on one of said links for releasing said dog, for the purpose specified.

24. The combination of a relatively stationary cover and a swinging cover; a pin carried by said stationary cover; upwardly-projecting links to which said swinging cover is pivotally secured, mounted on said pin; a clamping-jaw mounted on said pin; a spring connected to said pin and to said clamping-jaw for applying tension thereto, whereby said clamping-jaw is held normally against said stationary cover; an adjustable pawl connected to said swinging cover adapted to be shifted into or out of its operative position; a projecting tooth or lug connected with said clamping-jaw adapted to be engaged by said pawl when it is adjusted to its operative position; and a dog for locking said clamping-jaw in its open position, for the purpose specified.

25. The combination of a relatively stationary cover and a swinging cover; a clamping-jaw mounted on said stationary cover; a spring adapted to hold said clamping-jaw normally against said stationary cover; an adjustable pawl connected to said swinging cover adapted to be shifted into and out of operative position; a tooth or lug connected with said clamping-jaw adapted to be engaged by said pawl when it is in its operative position; means for returning said pawl to its initial position when said swinging cover is closed; a dog for lock-

ing said clamping-jaw in its open position; and means for releasing said dog when said swinging cover is closed, for the purpose specified.

26. The combination of a relatively stationary cover and a swinging cover; a clamping-jaw mounted on said stationary cover; a spring adapted to hold said clamping-jaw normally against said stationary cover; an adjustable pawl connected to said swinging cover adapted to be shifted into and out of operative position; a tooth or lug connected with said clamping-jaw adapted to be engaged by said pawl when it is in its operative position; a dog for locking said clamping-jaw in its open position; and means for releasing said dog when said swinging cover is closed, for the purpose specified.

27. The combination of a relatively stationary cover and a swinging cover; a clamping-jaw mounted on said stationary cover; a spring adapted to hold said clamping-jaw normally against said stationary cover; an adjustable pawl connected to said swinging cover adapted to be shifted into and out of operative position; a tooth or lug connected with said clamping-jaw adapted to be engaged by said pawl when it is in its operative position; means for returning said pawl to its initial position when said swinging cover is closed; and a dog for locking said clamping-jaw in its open position, for the purpose specified.

28. The combination of a relatively stationary cover and a swinging cover; a clamping-jaw mounted on said stationary cover; a spring adapted to hold said clamping-jaw normally against said stationary cover; an adjustable pawl connected to said swinging cover adapted to be shifted into and out of operative position; a tooth or lug connected with said clamping-jaw adapted to be engaged by said pawl when it is in its operative position; and a dog for locking said clamping-jaw in its open position, for the purpose specified.

29. The combination of a relatively stationary cover and a swinging cover; a clamping-jaw mounted on said stationary cover; a spring adapted to hold said clamping-jaw normally against said stationary cover; an adjustable pawl connected to said swinging cover adapted to be shifted into and out of operative position; a tooth or lug connected with said clamping-jaw adapted to be engaged by said pawl when it is in its operative position; and means for returning said pawl to its initial position when said swinging cover is closed, for the purpose specified.

30. The combination of a relatively stationary cover and a swinging cover; a clamping-jaw mounted on said stationary cover; a spring adapted to hold said clamping-jaw normally against said stationary cover; an adjustable pawl connected to said swinging cover adapted to be shifted into and out of operative position; and a tooth or lug connected with said

clamping-jaw adapted to be engaged by said pawl when it is in its operative position, for the purpose specified.

31. The combination of a relatively stationary cover and a swinging cover; a clamping-jaw mounted on said stationary cover; a spring adapted to hold said clamping-jaw normally against said stationary cover; an adjustable pawl connected to said swinging cover, adapted to engage said clamping-jaw when in its operative position; and means for returning said pawl automatically to its initial position, when said swinging cover is closed, for the purpose specified.

32. The combination of a relatively stationary cover and a swinging cover; a clamping-jaw mounted on said stationary cover; a spring adapted to hold said clamping-jaw normally against said stationary cover; and an adjustable pawl connected to said swinging cover,

adapted to engage said clamping-jaw when in its operative position, for the purpose specified.

33. The combination of a relatively stationary cover and a swinging cover; a clamping-jaw mounted on said stationary cover; a spring adapted to hold said clamping-jaw normally against said stationary cover; a pawl connected to said swinging cover, adapted to be thrown into and out of engaging position, adapted to engage said clamping-jaw when in its engaging position, for the purpose specified.

In witness whereof I have hereunto set my hand and seal in the presence of two witnesses.
